UNITED STATES PATENT OFFICE.

THOMAS R. GRIFFITH, OF DOVER, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed October 5, 1920. Serial No. 414,818.

This invention relates to electron discharge devices, one of the objects of the invention being to provide devices of this character which are suitable for use at high 5 voltages and capable of being readily and accurately made.

Another object of the invention is to provide electron discharge devices, adapted to have their anodes cooled by contact with a 10 suitable cooling medium, such as water or oil for example.

In the design of three element electron discharge devices to be used at high voltages, the question of insulation between elements becomes an important one. The so-called two-ended type of structure in which the anode as one unit is mounted on a stem 15 sealed into one end of the bulb and the grid and filament as another unit are mounted on a second stem sealed into the opposite end of the bulb, has given, in general, the required insulation. However, in making such a device the sealing in of one of the stems is also a "line up" process as the glass 20 blower must align the two stems by eye while the last seal is fluid. This process is difficult and also results in considerable 25 variation in impedance in different devices.

The present invention provides a stem on 30 which both electrode units may be mounted so that they may be aligned before sealing in, and yet the invention gives good high voltage protection as does the so called two-ended tube. Thus, the necessity of aligning 35 electrodes during sealing is avoided.

In the accompanying drawings Fig. 1 40 shows an electron discharge device embodying the invention. Fig. 2 shows the preferred form of device made in accordance with the invention, the anode being cooled by contact with a suitable fluid.

In Fig. 1 the electron discharge device 2 comprises envelope 3, the lower end 4 of 45 which is drawn in as usual and is sealed at 6 to an electrode supporting stem 7 which projects into the envelope. The stem 7 comprises an outer tubular portion 8 and an inner tubular portion 9, the top of the portion 8 being connected to the bottom of the portion 9 by a tubular portion 10. The top of the portion 10 is closed.

A metallic collar 12 is mounted on the portion 8 and carries metallic standards 13, which support anode 14 shown as a cylinder.

A metallic collar 16 is mounted on the portion 9 and carries metallic standards 17, which support a grid 20 and a cathode 21. Intermediate their ends the standards 17 carry a metallic ring or band 22 within which a lavite disc 23 is secured by means 55 of screws 24. At their upper ends, the standards 17 carry a band or ring 26 within which a lavite disc 27 is secured by screws 28. Grid wires 30 are fastened to the portion of the standards 17 between lavite discs 23 and 27. Wires 32 pass loosely through lavite disc 27 and are supported on springs 33 which rest on the disc 27. Wires 35 are fastened in the disc 23 and extend above the disc, two of them also extending below the 60 disc. The cathode filament 21 is mounted on the wires 32 and 35. Leading-in wires 37 and 38 for the cathode are attached to the wires 35 which extend below disc 23, wires 37 and 38 passing through the closed end 65 of the portion 9. Leading-in wire 39 for the grid is attached to one of the standards 17 and also passes through the closed end of tube 9. A leading-in wire 40 for the anode is sealed into the end of the vacuum tube 70 opposite the stem 7. It is evident that in Fig. 1 the grid surrounds the cathode and the cylindrical anode surrounds the grid and the cathode.

The stem 7 is preferably formed from a 75 tube having two portions of different diameters and a tapering connecting portion by heating the connecting portion and telescoping the portions of different diameters, at the same time, reducing the air pressure 80 in the tube to cause the connecting portion to lie close to the portion of a larger diameter. For a given distance between collars 12 and 16, these collars are more thoroughly insulated from each other the wider the 85 space between the tubular portions 9 and 10 in comparison to the space between the tubular portions 8 and 10, since in the finished vacuum tube the space between 9 and 10 is highly evacuated.

In Fig. 2 the electron discharge device 45 comprises envelope 46 which has one end drawn in at 47 as usual and sealed at 48 to electrode supporting stem 49 which projects inwardly into the envelope. The stem 49 100 comprises two concentric tubular portions 51 and 52 spaced apart except at the central portion where they are sealed together as

at 53. An anode 55, preferably of a metal such as platinum having a temperature coefficient of expansion substantially the same as that of glass, is sealed to the top of the 5 tubular portion 51. The anode is shown in the form of a dome forming a part of the wall of the envelope. A metallic collar 57 is mounted on the upper part of the tubular portion 52 and carries metallic standards 59 10 which support a grid 60 and a cathode 61, the cathode being shown as a looped filament. A lavite ring 63 is held between projections 64 on standards 59 and is tied to the standards by means of tie wires 65 passing 15 through the ring and the projections. Wires 66 fastened in the ring 63 support the cathode filament 61. The lower ends of the loops of the filament engage wires 67 slidably mounted in the lavite ring 69. Projections 20 on standards 59 prevent upward movement of ring 69, and springs 71 bearing against ring 69 force the wires 67 downwardly. A wire 72 is belted about the standards 59 to hold them in engagement 25 with the ring 69 and prevent them from spreading. The grid 60 comprises metallic rods 73 fixed in one of the rings 63 and 69 and slidably in the other of these rings, grid wires 75 being fastened to the rods 73. 30 Leading-in wires 77 and 78 for the cathode are attached to two of the wires 66, and leading-in wire 79 for the grid is attached to the top of one of the wires 73. A wire 81 connected to the lower end of the anode and 35 sealed through the tubular portion 51 near the lower end of said portion, forms the external connection for the anode. It is evident that in Fig. 2 the grid surrounds the hollow anode and the cathode surrounds the 40 grid and the anode. The lower end of the tubular portion 51 is closed by disc 83 through which pass two tubes 84 and 85, the tube 84 extending nearly to the upper end of the anode. A suitable cooling fluid 45 such as water or oil may be passed into the tube 84 and out of the tube 85, for cooling the anode 55 and associated parts.

The stem 49 is preferably made by telescoping two tubes 51 and 52 and sealing them 50 together intermediate their ends as at 53. The anode carrying its leading-in wire 81, is then sealed on to one end of the tubular portion 51. The collar 57 carrying the grid and cathode is mounted on the upper part 55 of the tubular portion 52. The three electrodes are properly aligned with respect to each other and the stem. Finally the stem is sealed to the envelope 47 as at 48 and the leads 77, 78 and 79 are sealed through the 60 upper end of the envelope 47.

The insulation between the elements of 65 electron discharge devices is of importance not merely from the point of view of the leakage resistance along the surface of the glass parts of the device, but also from the

point of view of the length of, and the gas pressure in, gaps between elements at different potentials, and from the point of view of the dielectric hysteresis and the conduction of current in the insulation between the 70 elements of different potentials. The collars 12 and 16 (Fig. 1) and 57 (Fig. 2) and the part of the anode 55 which is in contact with the glass part of the device are of large area, to reduce heating due to the dielectric 75 hysteresis, for the heating of glass not only tends to increase conduction current through the glass, but also increases the dielectric hysteresis loss in the glass.

The particular feature of supporting electrodes from a collar on the stem of a vacuum tube is the invention of William F. Hendry and is claimed in his application Serial No. 217,565, filed February 16, 1918 entitled—“Vacuum tubes”, assigned to the assignee of this application; the broad feature of supporting the electrodes from collars mounted on two concentric tubular portions on an inwardly projecting stem of a vacuum tube is the invention of Robert W. King and is claimed in his Patent No. 1,472,477, dated October 30, 1923, entitled “Electron discharge devices”, assigned to the assignee of this application, and the broad feature of the reentrant anode forming a part of the envelope of the vacuum tube and adapted to be cooled by contact with a suitable cooling fluid is the invention of Howard W. Weinhardt, Patent No. 1,432,931, dated October 24, 1922, entitled “Electron discharge devices” assigned to the assignee of this application. Therefore, these features are not claimed broadly and alone herein.

What is claimed is:

1. An electron discharge device comprising a vessel having a reentrant tubular stem, a metallic standard having a portion engaging said stem at a point intermediate the length of the stem, a plurality of electrodes carried by said stem, and an anode arranged within said electrodes.

2. An electron discharge device comprising a vessel having a reentrant stem, said stem comprising a plurality of coaxial portions, a standard surrounding one of said portions, a plurality of electrodes carried by said standard, and an anode carried by said other portion of the stem and arranged within said electrodes.

3. An electron discharge device comprising a tubular portion, a filamentary electrode, a metallic supporting member for said electrode, a band for attaching said member to said portion, and an anode within said electrode.

4. An electron discharge device having an electrode support, said electrode support comprising an inwardly projecting tubular portion and an electrode supporting portion rising from said tubular portion, said tubu-

- lar portion being open at its inner and outer ends, for the passage therethrough of a cooling liquid.
5. A vacuum tube comprising an anode and a cathode, and comprising a stem sealed into one end of said vacuum tube, said stem comprising two concentric tubular portions of different diameters projecting inwardly into said tube, a collar on the outer one of 10 said tubular portions, and a supporting connection between said collar and said cathode, said anode being supported from said inner tubular portion.
6. A vacuum tube comprising an anode, 15 a cathode, a grid, a stem sealed into one end of said vacuum tube, said stem comprising two concentric tubular portions of different diameters projecting inwardly into said tube, a collar on the outer one of said tubular portions, supporting connections from 20 said collar to said cathode and said grid, lead-in wires for said cathode and said grid at one end of said tube, and an external connection from said anode leading from 25 the other end of said tube, said anode being supported from said inner tubular portion.
7. A vacuum tube comprising an anode, a cathode, a stem sealed into one end of said vacuum tube, said stem comprising two tubular portions projecting inwardly into 30 said tube, one of said portions encircling the other, a collar on the outer one of said tubular portions, and a supporting connection between said collar and said cathode, said anode being tubular and being mounted on 35 said inner tubular portion and constituting a re-entrant part of the envelope of said tube.
8. An electron discharge device, comprising an enclosing vessel, an inwardly projecting stem, a tubular member extending through said stem, a substantially cylindrical cathode supported from said stem, and a cup-shaped anode within said cathode, said anode having its brim sealed in the end of 40 said tubular member whereby a cooling fluid may be supplied to the interior of said anode.

In witness whereof, I hereunto subscribe my name this 1st day of October A. D., 1920.

THOMAS R. GRIFFITH.
